UNITED STATES PATENT OFFICE

FLORIAN J. SHOOK, OF AKRON, OHIO, ASSIGNOR TO SEIBERLING RUBBER COMPANY,
A CORPORATION OF DELAWARE

BIAS CUTTING AND FABRIC STRIPPING MACHINE

Application filed August 24, 1929. Serial No. 388,195.

The present invention relates to improvements in machines for cutting fabric materials on the bias, and has for its general object to provide a machine of this character which will be simple in construction, efficient in operation, strong and durable in service, and economical in material and labor.

According to one feature of the invention, the improved machine is equipped with a horizontally disposed endless belt conveyor which is intermittently operated to advance the fabric sheet material (such as rubberized fabric used in tire manufacture), step by step and without tension, from a stock supply roll to a cutting position where it is cut diagonally by a rotary power-driven cutter. This cutter is mounted upon a carriage which is reciprocable on a frame or guide overlying the endless belt conveyor and extending transversely thereof at the desired angle, the frame being adjustable at will to vary the angle of the cut. The carriage is caused to reciprocate by power mechanism including a manually controlled clutch whereby the driving connection may be made or broken, as and when desired. At the cutting line, the fabric passes over a resilient metal strip or bar which is associated with the adjustable frame and which extends across the conveyor immediately above the upper surface thereof. This strip or bar facilitates the traversing movement of the cutter and protects the endless belt as well. A guide shoe is also mounted on the carriage and has a bifurcated portion straddling the lower edge of the cutter, this shoe being wedge shaped and adapted to slide under the fabric with the aid of the resilient metal strip, and to lift the fabric against the cutter during the cutting stroke of the carriage. On the return stroke of the carriage, the guide shoe passes over the fabric, leaving the same free to be fed forwardly preparatory to the next cut.

The feeding movement of the conveyor is effected automatically during the return stroke of the carriage. For this purpose a pressure cylinder, with a piston, is mounted at one side of the conveyor for moving a cross-head which carries a pawl or dog for engagement with a sprocket chain operative with the

endless belt. The admission and exhaust of fluid pressure to and from the opposite ends of the cylinder are controlled by a slide valve which is moved in one direction by the cross-head, and in the other direction by a separate piston in a pneumatic cylinder. Movement of the last-mentioned piston is controlled by a valve which is actuated by the carriage at the end of its cutting stroke. In addition to this automatic feed of the conveyor, a hand wheel is provided whereby the endless belt may be adjusted manually when required to determine accurately the line of the next cut.

Another feature of the invention resides in the provision of novel means for stripping the fabric from its liner as the fabric is fed to cutting position. Due to the firm surface union between the rubberized sheet and the liner with which it is wound, considerable force is necessary to separate them, and experience has shown that this can best be done in short quick jerks. For this purpose, therefore, the liner and the fabric sheet are drawn from the stock roll past an idler separating roller arranged between the two sheets and which causes them to diverge as they are unwound. The liner is wound up on an arbor or the like, while the rubberized fabric is guided over the liner wind-up roll and delivered to the conveyor of the bias cutter. The liner wind-up roll is adapted to be rotated, step by step, by a ratchet and pawl, the latter being actuated by a continuously operated power shaft. It is desirable however that the sheet separation be coordinated or substantially synchronized with the bias cutting operations, so that an amount of separated stock greatly in excess of that required will not be drawn off the stock roll. There is therefore associated with the pawl and ratchet device a saddle member which is adapted, in one position, to hold the pawl out of its operative engagement with the ratchet, and in another position to allow it to engage. The position of the saddle member is automatically controlled by a floating roller with which it is connected, said roller being supported by a slack portion of the separated rubberized fabric. As the amount of slack varies, the height of the roller will vary, and

such variations will be transferred to the saddle member to automatically engage and disengage the pawl and ratchet.

The foregoing and other objects, features, and advantages of the invention will be fully understood from the following description in connection with the accompanying drawings wherein the invention has been shown by way of illustration, and wherein,

Fig. 1 is a front side elevation of the improved machine;

Fig. 2 is a top plan view of the bias cutter proper;

Fig. 3 is a vertical transverse sectional view taken on line 3—3 of Fig. 2;

Fig. 4 is a fragmentary front side view showing the conveyor feed mechanism on a larger scale than in Fig. 1;

Fig. 5 is a sectional plan view taken on line 5—5 of Fig. 4, with parts broken away;

Fig. 6 is a view partly in elevation and partly in longitudinal section, showing the control valve for the conveyor feed;

Figs. 7 and 8 are views similar to Fig. 6, with the parts in different positions;

Fig. 9 is a vertical transverse sectional view taken on line 9—9 of Fig. 8;

Fig. 10 is a horizontal sectional view taken on line 10—10 of Fig. 8;

Fig. 11 is a diagrammatic perspective view of the conveyor feed mechanism;

Fig. 12 is an end view of the cutter-carriage and its driving means taken from the rear side of the machine;

Fig. 13 is a front view of the parts shown in Fig. 12, with parts of the conveyor in section;

Fig. 14 is a detail view of the shiftable motor support, the view being taken on line 14—14 of Fig. 13;

Fig. 15 is a rear view of the parts shown in Fig. 12;

Fig. 16 is a detail view, partly in section, of the carriage-controlled master valve for the conveyor feed mechanism;

Fig. 17 is an end elevation of the sheet separating mechanism of Fig. 1;

Fig. 18 is a fragmentary view on an enlarged scale, showing the novel actuating means for the liner wind-up arbor;

Fig. 19 is a front view of the mechanism of Fig. 18;

Fig. 20 is a side view of the same mechanism with parts broken away and parts in section;

Fig. 21 is a perspective view of the same parts, showing the pawl in its disengaged position;

Fig. 22 is a side elevation of a modified form of sheet separator; and

Fig. 23 is an end view of the same.

Referring to the drawings:

The improved bias cutting machine comprises a fixed main frame 10, having spaced parallel side rails 11, and supporting stand-

ards or legs 12, and a supplementary frame 13, which extends transversely over the main frame 10 and is adjustable angularly with reference thereto.

The supplementary frame 13 (see particularly Figs. 1, 2 and 3) comprises mounting brackets 14, arranged one at each side of the main frame and secured to the respective side rails 11, said brackets serving to adjustably support a pair of vertically spaced structural steel channel members 15 and 16, the former of which is spaced slightly above the main frame side rails, and the arrangement being such that the supplementary frame 13 is disposed diagonally or obliquely with reference to the main frame. The channel members 15 and 16 are connected together at their opposite ends, by spacing brackets 17 and 18, which respectively support sprocket wheels 19 and 20, the relations and functions of which will be more fully described hereinafter.

Also supported above the main frame 10, by extensions 21 of the leg members 12, is a horizontal table 22 having side rails 23 in which are journaled spaced shafts 24 and 25 (see also Fig. 4). Pulleys 26 and 27 are secured to the shafts 24 and 25 for the operation of an endless belt conveyor 28, the upper stretch of which is disposed immediately above the table 22. A sprocket chain 29 is mounted at one side of the conveyor 28 and adapted for movement therewith, and a hand wheel 30 is secured to the shaft 25 whereby the conveyor may be adjusted manually by the attendant of the machine. Ordinarily, the conveyor will be advanced automatically by mechanism which will later be described, supplemented by the hand operation, and as it is thus operated intermittently, a rubberized fabric sheet A is fed forwardly from a stock supply to a cutting position below the supplementary frame 13.

The fabric sheet material to be cut lies upon the belt conveyor 28 and is fed without tension, and as it reaches the cutting position, it is caused to pass over a separator bar 31 whereby it is raised slightly from the conveyor belt (see Fig. 3). This separator bar 31 is preferably in the nature of a thin flat strip of resilient metal which is slightly inclined in a transverse direction, and extends entirely across the main frame parallel with the channel bar 15. It is secured by means of screw yokes 32 to extension plates 33 on the spacing brackets 17 and 18, so that it can be adjusted with said frame to cut the material at different desired angles.

Mounted for reciprocation on the channel member 15 is a carriage 34, which comprises a substantially horizontal portion 35 and depending flange portions 36 and 37, respectively disposed at opposite sides of the channel member 15. Supporting wheels or rollers 38 are mounted on the inner faces of the

flange portions 36 and 37 and bear on the upturned flanges at the longitudinal edges of the channel member 15, thus facilitating movement of the carriage. A rotary cutter 39 is secured to one end of a shaft 40, which is journaled in the lower ends of the flange portions 36 and 37, the shaft being driven by a belt and pulley arrangement 42 from an electric motor 43 on the carriage portion 35. The rotary cutter 39 is preferably formed of a thin circular metallic disc having its periphery sharpened to a knife edge and provided with inwardly extending radial notches or incisions which form teeth. It has been found that a cutter of this character does not become gummed, and is therefore more effective than a plain circular cutter.

The cutter rotates in a plane directly over the separator bar 31 and has associated with it a bifurcated wedge-shaped guide shoe 47 which is adapted to slide under the fabric and raise the same against the edge of the cutter (see Fig. 3). The guide shoe 47 is suspended from the carriage by a bar 48, pivoted at 49, and the fork portions of the pointed bifurcated end of the shoe are disposed at opposite sides of the lower edge of the cutter. The guide shoe has its lower surface slightly inclined longitudinally with reference to the separator bar 31, and this form of guide shoe, in conjunction with the resilient nature of the separator bar, will permit the cutter on its return stroke to pass over the fabric without injuring it or without interfering with its forward feeding movement. If desired the separator bar 31, instead of being arranged strictly horizontal, may be disposed at a downward inclination from the near to the far edge of the fabric, in which case, as will be apparent, the guide shoe will avoid contact with the separator bar except at the beginning of the cutting stroke. With such a downwardly inclined bar, the resilient property is not so important, altho even so it would be preferable to have the strip mounted for yielding at the near edge of the fabric in order that the guide shoe may more easily pass beneath the fabric.

In order to reciprocate the carriage 34, it is attached in any suitable manner to a link chain 50 which runs over the sprocket wheels 19 and 20, before referred to. As best shown in Figs. 12, 13 and 15, the sprocket wheel 20 is secured to a shaft 51 which is journaled in the spacing bracket 18, and said shaft has keyed to its rear end a pinion 52 which meshes with a rack bar 53. This rack bar is adapted to be moved upwardly and downwardly in a vertical guide 54, through the medium of a pitman 55, the upper end of which is pivoted at 56 to the rack bar, and the lower end of which is pivoted at 57 to a crank 58. The crank 58 is rotatable with and by a gear 59 which meshes with a pinion 60, driven

through reducing gearing 61 from a shaft 62. This shaft 62 is also journaled in the bracket 18 and carries, intermediate its ends, a pair of relatively spaced friction discs 63 and 64. A friction drive wheel 65 is disposed between the discs 63 and 64 and adapted to engage with either one or the other of them, it being mounted upon the end of a shaft 66 of an electric motor 67.

The motor 67 is secured to an adjustable base plate 68 which is slidable in dovetail guides 69, and which has a pin and slot connection at 70 with one arm of a bell-crank lever 71 (Fig. 14). This bell-crank lever 71 is disposed in a recess below the base plate 68, being pivoted at 72 to a shelf portion 73 of the bracket 18, and having its other arm extending outwardly beyond one side edge of the plate 68. Thus, by movement of the bell-crank lever 71, the motor 67 will be bodily shifted so that the friction wheel 65 will engage either one of the discs 63 or 64, or will be in a neutral position, disengaged from both of them. The purpose of such shifting is either to render the cutter carriage inoperative, or to reverse the direction of its movement at any point in its cutting stroke.

The position of the motor 67 and its drive wheel 65 may be selectively controlled by the attendant from his station at the opposite side of the machine. To this end, the outer arm of the bell-crank lever 71 is attached, as at 75, to one end of a link 76, the other end of which is pivotally connected, as at 77, to the lower end of a rocker arm 78, which is pivoted at 79 intermediate its ends to the bracket 18. The upper end of the rocker arm 78 is connected, as at 80, to the extremity of a push rod 81 which extends across the machine and within the channel member 15 to a position adjacent the attendant's station near the hand wheel 30.

When the driving parts are in their intermediate or neutral positions, as shown in Figs. 12 and 13, the friction discs 63 and 64 and their shaft 62 are held against rotation by the engagement of a brake shoe 83 against the periphery of the disc 64. This brake shoe 83 is carried on the outer end of a lever 84, pivoted at 85 on the bracket 18, and is normally drawn toward the braking position by a tension spring 86. The inner end of the lever 84 is provided with an adjustable extension 87, whose upper edge is formed with a notch 88 in which a pin 89 on the rocker arm 78 is adapted to seat to define the neutral or braking position. As the rocker arm 78 is moved through the medium of the push rod 81, the pin 89 rides up out of the notch 88, pressing down on the edge of the lever 84, and rocking said lever about its pivot 85 to disengage the brake shoe 83 against the action of spring 86. At the same time, the motor is shifted, as above explained, to effect

engagement of the drive wheel 65 with either the disc 63 or 64.

When the driving connection is thus made, the carriage 34 is reciprocated back and forth across the conveyor, making its cutting stroke as it moves away from the front or operator's side of the machine. Due to the use of the crank 58, the speed of movement of the carriage varies, accelerating to a maximum at the middle of the stroke and decelerating to zero at the end of the stroke. This feature makes the cutting operation quite smooth and renders the machine substantially free from vibration.

The momentum of the carriage 34 is arrested at the end of its cutting and non-cutting strokes by means of shock absorbers 91 which extend upwardly adjacent the opposite ends of the channel member 15. Each of said shock absorbers comprises a casting 92 with a cylindrical bore 93, within which a piston 94 is slidably. The inner end of the cylindrical bore 93 is fitted with a guide 95 through which a piston rod 96 slides, said piston rod having a head portion 97 which is arranged in the path of movement of a strap 98 on the carriage 34. The outer end of the bore 93 is in communication with the atmosphere through a restricted orifice 99, and serves to confine a coiled compression spring 100 which normally tends to push the piston 94 and its rod 96 inwardly toward the carriage. Thus, just before the carriage reaches the end of its stroke, the strap 98 comes in contact with the head portion 97, moving the piston outwardly against the spring 100 and generating pressure within the bore 93. In effect, the bore 93 and piston 94 constitute a dash-pot which, by arresting the momentum of the carriage, relieves the chain 50 of heavy reversing stresses. This is advantageous because, in the ordinary operation of the machine, the carriage will be reciprocating constantly without actually stopping at the end of each stroke.

As previously stated, the conveyor belt 28 may be intermittently operated through the medium of hand wheel 30 or through automatic mechanism which will now be described. In actual practice, the automatic means will be employed to advance the fabric to approximately the correct position for cutting, and the manual means will be used, if necessary, for the final and exact setting.

Referring particularly to Figs. 1 and 4 to 11 inclusive, it will be seen that a pressure cylinder 105 is mounted in fixed position at the front side of the main frame 10 and below the link chain 29. Slidable within the cylinder 105 is a piston 106 secured to one end of a piston rod 107, whose opposite end carries a crosshead 108 outside the cylinder. This crosshead is in the nature of a rectangular bar, one end of which extends upwardly beside the lower stretch of the chain, and

the other end of which extends downwardly beside the adjacent rail 11 of the main frame. Pivoted to the upper end of the crosshead 108 is a gravity-actuated pawl 109 which is adapted to engage one of the links of the lower stretch of the chain 29, whereby movement of the piston 106 toward the right will be transmitted to the chain in feeding the conveyor forward. In the movement of the crosshead in the reverse direction, however, the pawl merely rides idly over the chain links until the cross head comes to rest in its normal position, as shown in Fig. 4, at which time the pawl is lifted out of engagement with the chain by a stationary finger 110 on the fixed main frame. In the disengaged position of the pawl, the chain is of course free to be moved in either direction by means of the hand wheel 30.

Movement of the piston 106 to and fro in actuating the crosshead 108 is effected by the admission and exhaust of pressure fluid, such as compressed air, to and from the opposite ends of the cylinder 105, through pipes 111 and 112, under the control of a slide valve 113.

The valve 113 (best shown in Figs. 6 to 10 inclusive) comprises a casing with a cylindrical barrel portion 114 secured to the side rail 11 of the main frame, and having a longitudinal bore lined by a fixed sleeve or bushing 115. At its front side, the interior of the barrel portion 114 is provided with three longitudinally spaced recesses 116, 117 and 118, with which the air pipes 111, 120 and 112 respectively communicate. The air pipes 111 and 112 lead to the opposite ends of the cylinder 105, as previously stated, while the pipe 120 leads from a suitable source of compressed air supply which may be alternately connected to and disconnected from the pipes 111 and 112 through the interior of the valve 113. In line with the recesses 116, 117 and 118, the sleeve 115 is provided with three series of radial ports 122, 123 and 124, as best shown in Figs. 7, 9 and 10. Also, the sleeve 115 and barrel portion 114 are provided at their lower side, and adjacent their opposite ends, with exhaust ports 125 and 126, which are open to the atmosphere.

Slidable within the sleeve 115 is a piston valve which, in the illustrated embodiment, comprises a tubular core 127 on which is screwed or otherwise secured a pair of cylindrical members 128 and 129 separated by a spacer 130. The inner ends of said cylindrical members 128 and 129 have a close sliding fit within the sleeve 115, while their outer ends are formed with flanges 131 and 132 to limit the movement of the valve. Intermediate their ends, said cylindrical members have annular grooves 133 and 134, whereby to provide communication between the ports 122 and 125, or between the ports 124 and 126. Packing rings 135 and 136 are associated with the spacer 130 and define an annular groove 130

137, the length of which is sufficient to bridge two of the three series of ports 122, 123 and 124 (Fig. 10) and to cut off the other series. Thus, in one position of the parts (Fig. 6), the ports 122 and 123 are in communication through the annular recess 137, permitting air under pressure to flow from the supply pipe 120 through pipe 111 and into the left hand end of cylinder 105, causing the piston 106 to move to the right. At the same time, the right hand end of the cylinder 105 is vented through the pipe 112, annular groove 134, and port 126. In the other position of the parts (Fig. 10), the ports 123 and 124 are in communication through the annular chamber 137, permitting air under pressure to flow from the supply pipe 120 through pipe 112 to the right hand end of cylinder 105, causing the piston 106 to move to the left. At this time, the left hand end of cylinder 105 is vented through pipe 111, space 133, and port 125.

The piston valve is initially held in the position shown in Fig. 6 by the engagement of the flange 131 against a shoulder 140 on a latch 141 pivoted at 142 on the top of the barrel portion 114. At its extremity, the latch 141 is formed with a curved nose portion 143 which, in its holding position, is disposed in the path of a beveled surface 144 of a trip collar 145 carried on a slidable rod 146. Disposed between the flange 131 and the trip collar 145 is a compression spring 147. The rod 146 slides through the tubular core 127 in a direction parallel with the center of the cylinder 105, extending a substantial distance therebeyond, as best shown in Figs. 1 and 4. Another collar 148 is secured to the rod 146 at a suitable distance from the trip collar 145, whereby to facilitate movement of the piston valve by the rod toward the left. As shown in Figs. 4, 5, and 11, the rod 146 at the extreme right is attached to a piston 150 in a pressure cylinder 151 secured to the side rail 11 near the operator's station at the hand wheel 30.

The cylinder 151 is normally supplied with air through a pipe 152 which leads from an automatic control 153 at the opposite side of the machine. This automatic control 153 (best shown in Fig. 16) comprises a box-like casing having internal partitions which define separate chambers 154, 155, and 156. A pair of poppet valves 157 and 158, mounted within the casing, permit or prevent communication between the chamber 155 and the chambers 154 and 156, said valves having stems 159 and 160 which extend outwardly from the casing and are fitted with enlarged heads 161 and 162, between which and the casing wall are compression springs 163. The pipe 152 leads into the chamber 155, while a similar pipe 164 leads into the chamber 154 from the main air supply pipe B with which the pipe 120 of valve 113 is connected.

Normally the valve 157 is closed and the valve 158 open, in which condition the chamber 155 is in communication with chamber 156 to permit venting through an opening 165 in the side of the casing. Supply of air to the pipe 164 is under manual control through the medium of a normally closed valve 166 which may be opened by depression of a pedal 167 at the operator's station (see Figs. 1, 4 and 5).

Pivoted at 168 between the outer ends of the valve stems 159 and 160 is a lever 169 which is adapted to swing in the common plane of said valve stems and which is provided with rollers 170 and 171 adapted to bear against the head portions 161 and 162. The lower end of this lever 169 is connected with a tension spring 172 whereby the lever is held in a tilted position, as indicated by full lines in Fig. 16, holding valve 158 open and permitting valve 157 to be closed by its spring 163. The upper end of the lever 169 is disposed in the path of movement of an adjustable stud 173 which projects from one side of the carriage portion 35. Consequently, as the carriage reaches the end of its cutting stroke, the stud 173 will engage the upper end of lever 169 and rock the same about its pivot 168 to the position shown by the dotted lines in Fig. 16 and by the full lines in Fig. 13. The valve 157 will then be opened and the valve 158 closed, permitting air to flow from chamber 154 through chamber 155 and out through pipe 152 to the cylinder 151. On the other hand, when the carriage starts its return stroke, the stud 173 breaks contact with the lever 169 and allows it to return to its original position to reverse the position of the two valves, and venting the cylinder 151 so as not to interfere with the subsequent operation of the rod 146 to which the piston 150 is attached.

As the compressed air enters the cylinder 151, it moves the piston 150 to the left, as shown in Figs. 4 and 11, carrying with it the rod 146 and moving the piston valve at 113 from its normal position at the right, as in Fig. 10, to the position at the left, as in Fig. 6. Air will now be supplied to the left-hand end of cylinder 105 as previously explained, causing the piston 106 to move to the right. As it does so, the crosshead 108 is moved by it in the same direction, and by engagement of the pawl 109 with one of the links of chain 29, the conveyor will be fed one step forward to advance the fabric material to the cutting position.

It is to be noted that the lower end of the crosshead 108 is slidable on the rod 146 and is adapted to be arrested in its conveyor feeding movement by a stop member 175 secured to said rod 146 at a point between the crosshead 108 and the cylinder 151. The stop member 175 may be set in different positions on the rod 146 to vary the throw of the crosshead in altering the advance of the conveyor.

for different widths of bias strips. As the crosshead, in its movement, comes into engagement with the stop member 175, it carries the stop member before it, correspondingly moving the rod 146 and its piston 150 and collars 148 and 145. As the collar 145 approaches the latch member 141, which in the meantime has been holding the valve 113 in the leftmost position shown in Fig. 6, the spring 147 becomes compressed. Then, when the beveled edge 144 finally raises the latch 141 to release the flange member 131, the valve will be moved to its original position at the right with a quick or snap action, whereupon air will be admitted to the right-hand end of cylinder 105, and vented from the other end of the cylinder. The piston 106 will thus be returned to the left-hand end of the cylinder, carrying with it the crosshead 108, and as it comes to rest at the left-hand end of its stroke, the pawl 109 will be raised out of engagement with the chain 29, leaving the conveyor free to be adjusted by the operation of the hand wheel 30.

25 The operation of the bias cutter will be clear from the foregoing description, but a brief recapitulation may be helpful. Assuming that the supplementary frame 13 has been adjusted to the proper angle for the desired cut, that the carriage 34 is at the operator's side of the machine ready to start its cutting stroke, and that the fabric A is in position for the first cut, the operator will close certain switches (not shown) to supply electric current to the motors 43 and 67 for the operation of the rotary cutter 39 and the carriage drive wheel 65. The operator will then depress the pedal 167 and hold it down to turn on the air-pressure, at the same time pushing the rod 81 away from him to release the brake shoe 83 and shift the motor 67 so that the drive wheel 65 will engage the disc 64 (the one usually employed for the regular drive). The disc 64 will thus be rotated, and through the gearing 61, 60, 59 and crank 58, the connecting rod will be driven to reciprocate the rack 53, which in turn oscillates the pinion 52. Movement of the pinion 52 is transmitted to the carriage by the sprocket 20 and chain 50, and as previously stated, the reciprocation of the carriage is synchronized with the throw of the crank, one rotation of the crank producing one complete reciprocation of the carriage. The carriage starts at slow speed but gradually accelerates to the center of the cutting stroke and then decelerates toward the end of the stroke, this variable speed of the carriage facilitating the cutting action and avoiding piling up of the fabric as the rotary cutter enters and leaves the opposite edges of the fabric. As the end of the cutting stroke is reached, the stud 173 trips the lever 169 to automatically actuate the conveyor advancing mechanism, which will have advanced the fabric to its next cutting position

long before the carriage has completed its return stroke. When the pneumatic conveyor-actuating means has completed its cycle of operation, the attendant may, if desired, adjust the conveyor forward or backward by means of hand wheel 30 to accurately position the fabric for the next cut. Once started, the machine will operate entirely automatically and without requiring any attention on the part of the operator except as to the adjustment of the conveyor after each advance when desired or required. If at any time the cutter becomes entangled with the fabric, the operator may stop the carriage at once by disengaging the drive wheel 65 from the disc 64 through the control rod 86, and may then back-up the carriage to any extent desired by engaging the drive wheel 65 with the opposite disc 63, which reverses the movement of the driving connections. So far as the conveyor is concerned, the operator may also exercise full control over its operation through the pedal 167, which when released instantly shuts off the air pressure from all the pneumatically operated parts.

Referring now particularly to Figs. 1 and 17 to 21 inclusive, the fabric separating means will next be described. The rubberized fabric is wound up with a liner in a stock roll 200 which is rotatably mounted by means of trunnions 201 in open bearing blocks 202 on upright side members 203 of a portable skid or frame 204. The rubberized fabric sheet A and the cloth liner C are drawn off the stock roll and separated by being passed around the opposite sides of a roller 205, after which the liner is wound up on a suitable arbor or roll 206, and the rubberized sheet carried over said roll 206 and delivered to the endless conveyor 28. Because of its action, the roll 206 will hereinafter be referred to as the feed roll. While it is not essential that the rubberized sheet A be passed over the feed roll, it is desirable to do so, because in that way the linear speed of the rubberized sheet is substantially the same as that of the liner, notwithstanding the fact that the speed of advance of the two sheets is gradually increased as the roll 206 increases in diameter by the continued winding of the liner thereon.

The feed roll 206 is journaled by means of trunnions 207 in bearing blocks 208, near the upper end of the side members 203, which are connected together by a brace or tie-rod 209. The separating roller 205 is similarly journaled in bearings 210 which are also secured to the side members 203. The location of the roller 205, in relation to the feed and stock rolls is such that the liner C will be pulled away from the tacky fabric sheet A, while the latter is allowed to travel in a straight path from the stock roll 200 directly to the feed roll 206. As the liner is wound upon the feed roll and as the latter is rotated, the rub-

berized sheet A is advanced to the conveyor, the arc of contact between the sheet and the liner roll being sufficient to feed the former steadily with little, if any, slippage.

Instead of being driven continuously, the feed roll 206 is rotated intermittently so that the respective sheets of material, at each successive impulse of the the roll 206, will be jerked apart in advance of the separating roller 205. The mechanism employed for this purpose consists of a ratchet wheel 211 which is keyed or otherwise secured to a transverse shaft 212 journaled in a pedestal 213 beside the skid 204. The shaft 212 is axially alined with feed roll 206, and the inner end thereof registers with one of the trunnions 207, so that a driving connection between the two may be quickly made or broken, as desired, by means of a sliding clutch or coupling 214. Rotation of the shaft 212 and ratchet wheel 211 is effected by a continuously rotating crank 215, driven by an electric motor 216, said crank being connected by a link 217 to an oscillating arm 218 on which is a pawl 219 adapted to engage the teeth of the ratchet wheel 211. The arm 218 is, of course, oscillatable on shaft 212, beside the ratchet wheel.

The pawl 219 is pivoted at 220 on the arm 218, and is under the influence of a tension spring 221 which tends to hold the nose of the pawl in engagement with the teeth of the ratchet wheel. As best shown in Figs. 20 and 21, the pawl 219 is provided with an extension or finger 222, which is disposed beside the ratchet wheel and substantially radial thereto. Under certain conditions, the pawl 219 is disengaged from the teeth of the ratchet wheel by a saddle member 223, adapted to be swung into and out of the plane of the pawl extension 222.

The saddle member 223 is substantially U-shaped, having an intermediate portion with an arcuate edge 224 concentric with the shaft 212, and two spaced parallel ends 225 and 226 which extend at opposite sides of said shaft and are secured to a rock shaft 227. This rock shaft is journaled, as at 228 and 229, in the ends of a bracket 230 secured to the pedestal 213, and is disposed in an inclined position substantially tangent to the shaft 212, as best shown in Fig. 20. When the saddle 223 is in the position shown in Fig. 19, it is clear of the pawl extension 222, leaving the pawl free to engage the teeth of the ratchet 211; but when the saddle 223 is in the position shown in Fig. 21, it engages the end of the pawl extension 222 and holds the pawl out of operative position. In this latter condition, the extension 222 of the pawl will ride freely over the arcuate edge 224 of the saddle as the arm 218 continues to oscillate, but the ratchet wheel will not be rotated because of the disengagement of the pawl.

The shifting of the saddle member 223 is

accomplished automatically in order to compensate for variation in the quantity of material used in the bias cutter as compared with the amount delivered to it by the separating means. In other words, it is desirable that the rubberized fabric be delivered to the bias cutter no faster than the rate at which it is used up. For this purpose, a sector member 231 is secured to the rock shaft 227 below the saddle 223 and extending in the opposite direction therefrom, said sector member having a pair of radially spaced lugs 232 and 233 between which is movable a lever 234 freely rotatable on the rock shaft. The extremity of the lever 234 is offset, as best shown in Figs. 18 and 20, and is connected with one end of a tension spring 235, whose other end is secured to the pedestal, the arrangement being such that the spring acts to hold the lever in either one extreme position or the other.

Adjacent its offset extremity, the lever 234 is provided with a slot 236, through which extends a horizontal stretch of a cable 237, which carries a pair of adjustably spaced collars 238 and 239 respectively disposed at opposite sides of the slotted end of the lever 234. The cable 237 is guided over grooved pulleys 240 and 241 which are supported on the pedestal 213, and over additional pulleys 242 and 243 which are supported by a horizontal bar 244 extending angularly over the separating mechanism.

The end of the cable 237 which depends from the pulley 243 is provided with a sling 245 having spaced bearing members 246 and 247 in which a sectional roller 248 is freely rotatable. The extremities of roller 248 are guided in slots 249 in upright side members 250 adjacent the receiving end of the main frame 10 of the bias cutter. The other end of the cable 237, which depends from the pulley 240, is provided with a weight 251 which almost counterbalances the roller 248. Thus, the roller 248 is held in a horizontal position, free to move upwardly and downwardly, such movement being controlled by the amount of slack in the rubberized fabric sheet A which has been separated from the liner and fed forwardly from the roll 206.

As shown in Fig. 1, the rubberized sheet A after leaving the feed roll 206 is run over a guide roll 252 from which it drops down in a festoon at the end of the conveyor and then up over another guide roll 253 to the conveyor. The guide roll 252 is vertically adjustable for the purpose of varying the arc of contact of the rubberized fabric sheet with the liner roll 206. The floating roller 248 is supported by the festoon, and obviously as the amount of slack in the sheet varies, said floating roller will be raised or lowered correspondingly.

With the parts in the relative positions

shown in Figs. 1 and 17 to 20 inclusive, the saddle member 223 is in its inoperative position, leaving the pawl 219 free to rotate the ratchet wheel 211 step-by-step as the arm 218 is oscillated. This motion of the ratchet 5 wheel is transmitted to the liner wind-up roll 206 through the coupling 214, causing the rubberized sheet A to be jerked from the liner and fed to the bias cutter. If for any reason the material is not used at the bias 10 cutter as rapidly as it is fed to it, the slack in the sheet at the festoon will be increased, allowing the floating roller 248 to drop down. As it does so, the cable 237 will move with it, the collar 238 finally coming into engagement 15 with the lever 236, and thereafter continued movement of the cable will swing said lever and move the saddle member 233 into the plane of the pawl extension 222. Thereafter, the pawl 219 will be held out of engagement 20 with the teeth of the ratchet 211 so that the rotation of the feed roll will temporarily stop until the extra slack in the fabric has been used up. With this arrangement, a supply of freshly separated stock is 25 always available.

A modification of the fabric separating means is shown in Figs. 22 and 23. In this form, there is a plurality of stock supply rolls 260, 261, mounted on a turret arrangement which also accommodates a corresponding number of liner wind-up or feed rolls 262 and 263. The turret comprises a pair of spaced rotatable discs or spider members 264 and 265 secured to the opposite ends of a shaft 266, which is journaled at 267 and 268 on a suitable frame. Either one of the stock rolls 260 or 261 may be selectively positioned for unwinding, and to facilitate adjustment 30 of the turret for this purpose, a power mechanism is employed. Such power mechanism comprises a worm wheel 269 on one end of the shaft 266, meshing with a worm or screw 270 which is driven through bevel gears 271 and sprocket chain 272 from the motor 216. Driving connection between the bevel gears 271 and the sprocket chain 272 may be made and broken through a jaw clutch 273, manually controlled by a rocking 45 handle 274.

The motor 216 also drives the crank 215, link 217, and oscillating arm 218 as previously described to operate a ratchet mechanism which is enclosed in a suitable casing 55 275. This ratchet mechanism is substantially the same as that employed in the first-described form of the invention, with the exception that the rocking lever 234 which shifts the saddle member, cooperates 60 with a vertical stretch of the cable 237 instead of with a horizontal stretch. The ratchet shaft of said mechanism extends through the casing 275, and is provided with a sliding clutch member 276 for engagement 65 with a mating clutch member 277 on the liner

wind-up arbor. Said clutch member 276 may be shifted axially to make and break the driving connection by means of a yoke 278 and handle 279.

A rod 280 is adapted to rock with the yoke 70 278, and is provided at its lower end with an offset portion 281 which cooperates with the handle 274 to prevent driving connection of both clutches at one time. Thus, as the yoke 278 is rocked to engage the clutch member 276 with the member 277, the offset 281 will be swung to a position immediately above the inner end of the handle 274, preventing subsequent rocking of said handle. In other words, the two clutches 273 and 276 are independently operated manually, but the arrangement is such that only one of them can be engaged at a time. The driving connection for the feed roll must be broken before the turret can be shifted, and vice versa. 80

With this turret arrangement, supply rolls of different width stock or of different kinds of stock may be mounted together on one turret, and the change from one to the other can be very easily effected. 90

In order to prevent running off of material from the stock roll which is in the inoperative position, each of the stock roll arbors is provided with a drum 282 at the outer side of the spider 264, and said drum is adapted to be engaged by a brake band 283. One end of each brake band is anchored at 284 on the spider, and the other end fitted with a screw-threaded stud, for cooperation with a wing nut 285. By adjustment of the wing nut, the brake band may be either tightened or loosened, as desired. The resistance offered by these brake bands to the unwinding of the stock rolls is not objectionable; on the contrary, it may be desirable in effecting the separation of the two sheets and in preventing the overrunning of the stock rolls near the end of the unwinding operation. 105

The invention has been shown merely in preferred form and by way of example, and obviously many modifications and variations may be made in the details of construction or arrangement without departing from the spirit of the invention. It should be understood, therefore, that the invention is not limited to any form or embodiment except insofar as such limitations are specified in the appended claims. 110

Having thus described my invention, what I claim is:

1. A bias cutting machine comprising, in combination, means for advancing fabric to cutting position, a rotary power-driven cutter movable transversely of the fabric to sever the same into successive bias-cut strips, and power mechanism for reciprocating the cutter with a varying speed which accelerates from the beginning to the middle of the cutting stroke, and decelerates from the middle to the end of said stroke. 125

2. A bias cutting machine comprising, in combination, a conveyor for advancing fabric to cutting position, a transversely extending frame disposed obliquely above the conveyor, a carriage mounted for reciprocation on said frame and equipped with a rotary power-driven cutter, power mechanism for reciprocating said carriage, and reversible clutch devices incorporated in the operative connections between the power mechanism and the carriage, said clutch devices being movable to a neutral position to disconnect the carriage from the power mechanism when desired. 70
- 5 10 15 20 25 30 35 40 45 50 55 60 65 70 75 80 85 90 95 100 105 110 115 120 125
3. A bias cutting machine comprising, in combination, a conveyor for advancing fabric to cutting position, a transversely extending frame disposed obliquely above the conveyor, a carriage mounted for reciprocation on said frame and equipped with a rotary power-driven cutter, power mechanism for reciprocating said carriage, means for disconnecting the power mechanism from the carriage at will, and an automatic brake for stopping the movement of the carriage upon disconnection of the power mechanism. 80
4. A machine as set forth in claim 2 wherein in the reversible power mechanism comprises sprocket wheels disposed at the opposite ends of the transversely extending frame, an endless chain running over said sprocket wheels and attached to the carriage, a pinion mounted for rotation with one of said sprocket wheels, a rack bar meshing with said pinion, a crank and connecting rod for reciprocating the rack bar, a pair of spaced coaxial friction discs geared for rotation with the crank, a bodily shiftable motor, a friction wheel driven by the motor and adapted to engage either one of said friction discs whereby to drive the same, or to be disengaged from both of them, and manually-controlled means for shifting the motor to make and break the driving engagement of the friction wheel. 95
5. A machine as set forth in claim 2 wherein in the reversible power mechanism comprises sprocket wheels disposed at the opposite ends of the transversely extending frame, an endless chain running over said sprocket wheels and attached to the carriage, a pinion mounted for rotation with one of said sprocket wheels, a rack bar meshing with said pinion, a crank and connecting rod for reciprocating the rack bar, a pair of spaced coaxial friction discs geared for rotation with the crank, a bodily shiftable motor, a friction wheel driven by the motor and adapted to engage either one of said friction discs whereby to drive the same, or to be disengaged from both of them, manually-controlled means for shifting the motor to make and break the driving engagement of the friction wheel, and a brake acting upon one of the friction discs to stop the carriage automatically when the driving engagement of the friction wheel is broken. 100
6. A bias cutting machine comprising, in combination, a conveyor for advancing fabric to cutting position, a rotary power-driven cutter movable transversely of the conveyor to cut the fabric on a bias, and fluid-pressure-actuated means for operating the conveyor step-by-step in feeding the fabric to cutting position. 105
7. A bias cutting machine comprising, in combination, a conveyor for feeding fabric to cutting position, a transversely extending frame disposed obliquely above the conveyor, a carriage reciprocable on said frame, a rotary power-driven cutter supported by said carriage, means for reciprocating the carriage in a cutting stroke and a non-cutting return stroke, and fluid-pressure-actuated means controlled by the carriage at the end of each cutting stroke for moving the conveyor step-by-step in feeding the fabric to cutting position. 110
8. A bias cutting machine comprising, in combination, a conveyor for feeding fabric to cutting position, a transversely extending frame disposed obliquely above the conveyor, a carriage reciprocable on said frame, a rotary power-driven cutter supported by said carriage, means for reciprocating the carriage in a cutting stroke and a non-cutting return stroke, and means for intermittently moving the conveyor in feeding the fabric to cutting position, said means including a pressure cylinder, an actuating member movable by fluid pressure in said cylinder and having operative connection with the conveyor, a valve for controlling admission and exhaust of pressure fluid to and from the opposite ends of said cylinder, and means engageable by the carriage at the end of each cutting stroke to operate said valve whereby to initiate movement of the actuating member. 115
9. In a bias cutting machine, the combination with an endless belt conveyor and a reciprocating cutter carriage, of means for intermittently feeding the conveyor, said means comprising an endless chain at one side of the conveyor and movable therewith, means including a pressure cylinder and piston for actuating said chain to move the conveyor, a valve for controlling admission and exhaust of pressure fluid to and from the opposite ends of said cylinder, and means including a supplementary pressure cylinder for initially moving said valve, said supplementary pressure cylinder being initially controlled by a valve actuated by the cutter carriage at the end of each cutting stroke. 120
10. In a bias cutting machine, the combination with an endless belt conveyor and a reciprocating cutter carriage, of means for intermittently feeding the conveyor, said means comprising an endless chain at one side of the conveyor and movable therewith, a pressure 125
- 130

cylinder having its axis parallel with the plane of movement of said chain, a piston 5 slidable within said cylinder and having a piston rod extending outwardly through one end thereof, a crosshead attached to the outer end of said piston rod and carrying a pawl for driving engagement with said chain in one direction of movement, a slide valve for controlling admission and exhaust of pressure fluid to and from the opposite ends of 10 said cylinder to control the movements of the piston and crosshead, pneumatic means controlled by the carriage for moving said valve in one direction, and means cooperating with the crosshead to move said valve in the other direction.

11. In a bias cutting machine, the combination with an endless belt conveyor and a reciprocating cutter carriage, of means for automatically advancing the conveyor step-by-step, and manual means for adjusting the conveyor independently of said automatic means.

12. A bias cutting machine comprising, in combination, an endless belt conveyor for advancing fabric to cutting position, a carriage mounted for reciprocation transversely over said conveyor and carrying a rotary power-driven cutter to cut the fabric on a bias, pneumatic means for advancing the conveyor step-by-step to feed the fabric, and means for manually controlling said pneumatic means.

13. A bias cutting machine comprising, in combination, an endless belt conveyor for advancing fabric to cutting position, a carriage mounted for reciprocation transversely over said conveyor and carrying a rotary power-driven cutter to cut the fabric on a bias, pneumatic means for advancing the conveyor step-by-step to feed the fabric, said means including a pressure cylinder at one side of the conveyor and fitted with a piston, a crosshead movable by the piston, a pawl carried by the crosshead to engage a portion of the conveyor in one direction of movement, a slide valve for controlling admission and exhaust of pressure fluid to and from the opposite ends of the cylinder, said valve being mounted on a sliding rod, means for moving the valve in one direction, and means cooperating with the crosshead to move the valve in the other direction whereby to automatically reset the parts.

14. A bias cutting machine comprising, in combination, an endless belt conveyor for advancing fabric to cutting position, a carriage mounted for reciprocation transversely over said conveyor and carrying a rotary power-driven cutter to cut the fabric on a bias, pneumatic means for advancing the conveyor step-by-step to feed the fabric, said means including a pressure cylinder at one side of the conveyor and fitted with a piston, a crosshead movable by the piston, a pawl carried

by the crosshead to engage a portion of the conveyor in one direction of movement, a slide valve for controlling admission and exhaust of pressure fluid to and from the opposite ends of the cylinder, said valve being mounted on a sliding rod, means automatically controlled by the carriage at the end of its cutting stroke to move the slide valve in one direction, whereby to advance the conveyor, and an adjustable stop member mounted on the valve rod in the path of movement of the crosshead, whereby to move the valve automatically in the other direction to reset the parts.

15. A bias cutting machine comprising, in combination, a conveyor for advancing fabric to cutting position, a rotary power-driven cutter movable transversely of the conveyor to cut the fabric on a bias, automatic means for reciprocating the cutter in a cutting stroke and a non-cutting return stroke, and means for automatically moving the conveyor intermittently to feed the fabric to cutting position during the return stroke of the cutter.

16. A bias cutting machine comprising, in combination, an endless belt conveyor for advancing fabric to cutting position, a transversely extending frame disposed obliquely above the conveyor, a carriage reciprocable on said frame, a rotary power-driven cutter supported by the carriage, a sprocket chain associated with the frame and to which the carriage is connected, constantly operated power-driven means for imparting reverse movements to said sprocket chain whereby automatically to reciprocate the carriage and with it the cutter, and means automatically controlled by the carriage at the end of its cutting stroke to advance the conveyor whereby to feed the fabric to its next cutting position.

17. A bias cutting machine comprising, in combination, an endless belt conveyor for advancing fabric to cutting position, a transversely extending frame disposed obliquely above the conveyor, a carriage reciprocable on said frame, a rotary power-driven cutter supported by the carriage, a sprocket chain associated with the frame and to which the carriage is connected, constantly operated power-driven means for imparting reverse movements to said sprocket chain whereby automatically to reciprocate the carriage and with it the cutter, and pneumatically actuated means controlled by the carriage at the end of its cutting stroke to advance the conveyor whereby to feed the fabric to its next cutting position.

18. A bias cutting machine comprising, in combination, a conveyor for advancing fabric to cutting position, a rotary power-driven cutter movable transversely of the conveyor to cut the fabric on a bias, power-driven means for reciprocating the cutter in a cutting

ting stroke and a non-cutting return stroke, and fluid-pressure-actuated means for advancing the conveyor during the return stroke of the cutter.

19. A bias cutting machine comprising, in combination, a conveyor for advancing fabric to cutting position, a transversely extending frame disposed at an angle to the path of movement of the conveyor, a carriage reciprocable on said frame, a rotary power-driven cutter supported by said carriage for cutting the fabric, power-driven means including a manually-controlled clutch for reciprocating the carriage, pneumatically actuated means for advancing the conveyor, and means for manually adjusting the conveyor independently of said pneumatically actuated means.

20. A bias cutting machine comprising, in combination, an endless belt conveyor for advancing fabric to cutting position, a rotary power-driven cutter movable transversely over the conveyor to cut the fabric on a bias, reversible power-driven means for reciprocating the cutter, pneumatic means for advancing the conveyor step-by-step during the return strokes of the cutter, separate means for manually controlling reciprocation of the carriage and the movement of the conveyor, and means for manually adjusting the conveyor independently of said pneumatic means.

21. A bias cutting machine comprising, in combination, a conveyor for advancing fabric to cutting position, a rotary power-driven cutter movable transversely of the fabric to sever the same into successive bias-cut strips, power-driven means for reciprocating the cutter over the conveyor, and means for stopping said power means and reversing its operation at any point in the cutting stroke.

22. A bias cutting machine comprising, in combination, a conveyor for advancing fabric to cutting position, a rotary power-driven cutter movable transversely of the fabric to sever the same into successive bias-cut strips, power-driven means for reciprocating the cutter over the conveyor, and means for stopping and starting the operation of said power-driven means in any position of the cutter, whereby the cutter is maintained under manual control at all times.

23. A bias cutting machine comprising, in combination, a conveyor for advancing fabric to cutting position, a rotary power-driven cutter movable transversely of the conveyor to cut the fabric on a bias, power means for moving the cutter back and forth across the conveyor, additional power means disconnected from the cutter power means for operating the conveyor step by step, and automatic means for controlling the operation of the conveyor power means to synchronize the operation of the conveyor with the movements of the cutter.

24. A bias cutting machine comprising, in combination, a conveyor for advancing fabric to cutting position, a rotary power-driven cutter movable transversely of the conveyor to cut the fabric on a bias, continuously operated power means for moving the cutter back and forth across the conveyor, intermittently operated power means disconnected from the cutter power means for operating the conveyor step by step, and automatic means for inaugurating the operation of the latter power means at the end of each cutting stroke of the cutter.

25. A bias cutting machine comprising, in combination, an endless belt conveyor for advancing fabric to cutting position, a transversely extending frame disposed obliquely above the conveyor, a carriage reciprocable on said frame, a rotary power-driven cutter supported by the carriage, constantly operated power means for imparting reverse movement to the cutter carriage to reciprocate the cutter across the conveyor, additional power means operable in cycles and adapted at each cycle of operation to operate the conveyor one step forward in advancing the fabric to cutting position, and means actuated by the cutter carriage at the end of each cutting stroke to initiate the operation of said conveyor power means.

26. In a bias cutting machine, the combination with a conveyor for advancing fabric to cutting position, and a cutter carriage adapted to travel transversely over said conveyor, of power-driven means, including a crank, for reciprocating the carriage with a varying speed which accelerates from the beginning to the middle of the cutting stroke, and decelerates from the middle to the end of the stroke.

In testimony whereof, this specification has been duly signed by:

FLORIAN J. SHOOK.
